CLAIM

The ornamental appearance for a combination cap and nozzle unit, as shown and described.

DESCRIPTION

FIG. 1 is a top plan view of a combination cap and nozzle unit embodying our new design, in a closed configuration;

FIG. 2 is a rear elevational view thereof;

FIG. 3 is a front elevational view thereof;

FIG. 4 is a right side elevational thereof, the opposite side being a mirror image thereof;

FIG. 5 is a bottom plan view thereof;

FIG. 6 is an isometric view thereof;

FIG. 7 is a top plan view of the combination cap and nozzle unit in an open configuration to more clearly illustrate the combination cap and nozzle unit thereof;

FIG. 8 is a front elevational view of the combination cap and nozzle unit with the cap removed to more clearly illustrate the nozzle thereof;

FIG. 9 is a right side elevational view of the combination cap and nozzle unit in an open configuration, the opposite side being a mirror image thereof;

FIG. 10 is a rear elevational view of the combination cap and nozzle unit with the cap removed to more clearly illustrate the nozzle thereof;

FIG. 11 is a bottom plan view of the combination cap and nozzle unit in an open configuration thereof;

FIG. 12 is an isometric view thereof;

FIG. 13 is a right side elevational view thereof, with a partial cutaway of the cap to more clearly disclose the tab of FIG. 12; and,

FIG. 14 is a partial bottom plan view of the cap portion thereof.
